UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A BASE FOR LAMPS.

SPECIFICATION forming part of Design No. 23,418, dated July 3, 1894.

Application filed June 7, 1894. Serial No. 513,827. Term of patent 3½ years.

To all whom it may concern:

Be it known that I, LOTHAR VON GRAVE, a subject of the Emperor of Germany, residing at Wallingford, New Haven county, in the State of Connecticut, have invented and produced a new and original Design for a Base for Lamps, &c., of which the following is a specification, reference being had to the accompanying drawing, forming part of the same, and wherein the figure shows a perspective view of a lamp base embodying my design.

The essential features of my design consist in a series of ornamental bars projecting from the upper ornamental portion of the base and connecting with scroll-like portions which constitute the feet and on which are allegorical figures.

Reference being had to the drawing, a represents the series of ornamental bars projecting from the upper ornamental portion b of the base. The bars a connect with scroll-like portions c which constitute the feet of the base and on which are allegorical figures d.

What I claim is—

The design for a base for lamps &c. substantially as herein shown and described.

LOTHAR VON GRAVE.
